UNITED STATES PATENT OFFICE.

THOMAS MIDGLEY, JR., OF WORTHINGTON, OHIO, ASSIGNOR TO THE NATIONAL CASH REGISTER COMPANY, OF DAYTON, OHIO, A CORPORATION OF OHIO, (INCORPORATED IN 1906.)

DIFFERENTIAL MECHANISM FOR ACCOUNTING-MACHINES.

1,190,443.

Specification of Letters Patent.

Patented July 11, 1916.

Application filed October 11, 1913. Serial No. 794,723.

To all whom it may concern:

Be it known that I, THOMAS MIDGLEY, Jr., a citizen of the United States, residing at Worthington, in the county of Franklin and 5 State of Ohio, have invented certain new and useful Improvements in Differential Mechanism for Accounting-Machines, of which I declare the following to be a full, clear, and exact description.

10 The present invention relates to improvements in cash registers or accounting machines and refers particularly to improvements in the differential mechanism for actuating the totalizer and in the mechanism 15 by which the transfer is made from totalizer wheels of lower to wheels of higher denomination.

The improvements are primarily intended for that type of machine in which there are 20 independent actuators for totalizer wheels of different denominations with a series of keys or corresponding devices by which the different extents of rotation to be imparted to a totalizer element by its actuator may 25 be determined.

In the drawings and the following description the improvements are shown embodied in a cash register of the two motion type, that is, a register in which the operation 30 of a key predetermines the extent of rotation which is to be given a totalizer wheel by the actuator when said actuator is driven by a subsequent operation of the operating mechanism. It will be apparent 35 however, when reading the description in connection with the drawings, that the use of the improvements is not limited to such a machine but that they can be embodied in various forms in many other types of cash 40 registers and accounting machines. It will also be apparent that the actuator mechanism disclosed can, with a few changes which will readily suggest themselves, be used for driving parts other than the elements 45 of the totalizer. It is not, therefore, the desire to be limited to any particular use of this actuator mechanism or to any particular embodiment of the improvements as a whole.

One of the objects of the invention is to 50 provide a simply constructed machine in which the totalizer and its actuators are at all times in engagement. Such a construction obviously minimizes wear and the liability of mechanical trouble usually existing 55 where either the totalizer or the actuators must be moved to bring the two into engagement as a preliminary to the entry of items in the totalizer. While it is not broadly new to have the totalizer in engagement at all 60 times with its actuators, in previous constructions of the kind, so far as known to the applicant, the actuators are differentially moved, the extents of their movements depending upon the values registered, and 65 some form of one-way driving connections between the actuators and the totalizer has been provided, usually ratchet and pawl devices arranged to allow the actuators to return to normal position after the actuating 70 movement without reversely rotating the totalizer wheels. In the present construction each actuator is given an invariable rectilinear reciprocation on each operation of the register and depression of any one of 75 a series of keys renders the corresponding actuator effective to turn its totalizer wheel the proper number of divisions to represent the key pressed, after which the actuator is automatically rendered ineffective to 80 turn the wheel during the rest of its reciprocation.

Another object of the invention is to further simplify the construction by rendering unnecessary separate retaining devices for the totalizer wheel, as the actuator cannot only be rendered effective to rotate its totalizer wheel, but during the part of its reciprocation that the actuator is ineffective to rotate the wheel it is effective to 90 hold the wheel stationary.

Another object of the invention is to provide improved mechanism for carrying or transferring from wheels of lower to wheels of higher denomination. When a totalizer 95 wheel is rotated past "9" during an adding operation, devices are tripped which render the next higher actuator effective to rotate

its totalizer wheel one division just before the end of its normal actuating stroke. At the end of this actuating stroke and just before starting on the return to normal stroke 5 the actuator restores the transfer devices to normal position.

With these and incidental objects in view, the invention consists in certain novel features of construction and combinations of 10 parts, the essential elements of which are set forth in appended claims and a preferred form of embodiment of which is hereinafter described with reference to the drawings which accompany and form part 15 of the specification.

Figure 1 is a vertical cross section of the machine taken on the line $x-x$ of Fig. 2, and partly broken out at the top. Fig. 2 shows features of the actuators and transfer 20 mechanism. Fig. 3 is the same as Fig. 1 with the mechanism in partially operated position. Fig. 4 is a rear view showing in detail features of the transfer tripping devices. Fig. 5 is a detail of one of the actuators controlling elements.

Described in a general way the illustrative register with the improvements embodied consists of a plurality of banks or sections, the number depending upon the 30 registering capacity desired. One of these sections is shown in Fig. 1. Each bank comprises a totalizer element and an actuator therefor, a vertical row of keys ranging from "1" up to "9" and differential mechanism 35 controlled by the keys and in turn controlling the totalizer actuator. Each actuator is carried bodily by an element connected to driving mechanism common to all of the banks and which reciprocates the actuator 40 an invariable distance on every operation of the driving mechanism. The movements of the totalizer wheel are imparted by the actuator during the stroke of the latter in one direction. This stroke is herein usually referred to as the actuating stroke. The other 45 stroke or half of the reciprocation, that is, the return to normal stroke, is idle so far as rotation of the totalizer wheel is concerned; but, as indicated above, during this return to 50 normal stroke as well as the part of the actuating stroke that the actuator is not driving the totalizer wheel, it is effective to retain the wheel in position. Rigidly connected to the 55 totalizer wheel is a gear having spirally disposed teeth, and the actuator, which is in the form of a sleeve capable of both rotary and vertical movement carries on its face several parallel helical threads, at least one of which is at all times in engagement with the totalizer wheel gear. When a key is pressed in and the register operated the carrier for the 60 actuator is reciprocated as above described; but the actuator is prevented from rotating during a part of the actuating stroke proportional to the value of the key depressed.

This causes the helical threads of the actuator to act against the teeth of the totalizer gear the same as the teeth of a rack, rotating the totalizer gear and its wheel. As soon as the wheel has been rotated the desired number 70 of divisions to represent the key used, the element which prevents rotation of the actuator is disengaged and another element engages the helical threads of the actuator and causes the actuator to rotate during the rest 75 of its reciprocation so that the threads on the actuator run idly across the face of and between the teeth of the totalizer gears. This prevents the gear and its attached wheel from turning.

The transfer from an adding wheel of lower to a wheel of higher denomination is accomplished by stopping the rotation of the next higher actuator near the end of the actuating stroke, causing the actuator and 80 its carrier to move rigidly together and operate as a rack just long enough to turn the connected adding wheel one division. The actuator threads are not helical at the transfer operating portion of the actuator but extend longitudinally. When the lower 85 denomination adding wheel is turned past "9," devices are tripped to project an element forward to engage the threads of the next higher actuator during its actuating stroke. This element causes the actuator to begin 90 rotating at the proper time, or if it is then rotating, to continue the rotation as long as it is in engagement with the helical portion of the threads; but as soon as the longitudinal 95 portion of the threads, which is above the actuating portion of the actuator, comes in contact with said element, rotation is stopped and the actuator travels rigidly with its carrier just long enough to rotate its adding 100 wheel a division. Just at the end of the transfer operation and before the actuator starts to return to its normal position a flange carried by the lower order actuator engages the transfer devices and restores them 105 to normal position.

Described in detail and with reference to the drawings the driving shaft 1 (Fig. 1) is given a complete rotation clockwise on every 110 operation of the register either by means of a manually operable handle or by means of a motor. Attached to the shaft 1 is a plurality of cams 2, a pair for each bank or section of the machine. For reasons appearing later these pairs of cams are arranged 115 spirally around the shaft 1. A three-armed lever 3 journaled on a stub shaft 4 in the machine frame carries on its lower arms oppositely extending anti-friction rollers 5. Each of these rollers rides on the face of one 120 of the pair of cams provided for that particular bank. The shape and arrangement of a pair of these cams is such that on every rotation of the shaft 1 the lever 3 will be rocked first clockwise and then counter- 125 clockwise.

clockwise. Loosely mounted on a rod 6 extending through the machine frames is a plate 7 for each bank of the machine. Links 8 connect these plates and the upper arms of the levers 3 so that when the levers 3 are rocked in the manner described the plates 7 will also be rocked about the shafts 6 and, as the links connect the plates 7 and the arms 3 above their respective centers, the plates 10 always rock with the levers first clockwise and then counter-clockwise.

The rearwardly extending portion of the plate 7 is in the form of a sector 9 with its teeth in fixed engagement with the teeth of 15 a rack 10. The lower end of this rack is guided by a slot in a bracket 30 carried by the back machine frame 11 while at its other end the rack carries an extension 12 connected to the hub 13 of the actuator 14. The 20 actuator is in the form of a sleeve loosely mounted on a rod 15 which is rigidly secured at either end in the brackets 16 and 30 fastened to the machine back frame 11. The connection between the actuator hub and the 25 extension 12 of the rack 10 is of such a nature that the actuator is free to rotate about the rod 15 but cannot move longitudinally independent of the rack. By tracing the movement through the parts described, 30 it will be seen that every time the shaft 1 is given a rotation the rack 9 will be reciprocated an invariable distance first down and then back up to normal position, and that the actuator 14 will be given a corresponding invariable movement along the rod 15.

Loosely mounted on the rod 6 and beside the plate 7 is an arm 17 with a link 18 and a bell crank lever 19 attached by the pivots 20 to the forward end of the arm. This link 40 and bell crank lever carry on pivots 21 and 22 a latch 23 which is at all times drawn rearward by a spring 24 so that the rear end of the latch 23 is normally held in engagement with a cut 25 in the plate 7, establishing an operating connection between the plate 7 and the arm 17 so that the two will move together as long as the latch 23 remains in engagement with the cut 25 in the plate. Unless a key in the bank is depressed 50 the latch 23 is withdrawn from the cut 25 in the plate 7 at the very beginning of the operation by a pawl 26 which is pivoted to the machine frame at 27 and at all times urged by the spring 28 into the position shown in 55 Fig. 1 with its nose 29 resting in the path of a block 31 rigidly secured to the forward end of the bell crank lever 19. When the plate 7 is rocked clockwise by an operation of the driving mechanism, the arm 17 and 60 the parts pivoted thereto will, owing to the fact that the latch 23 is at the time seated in the cut 25, also start to move clockwise. However, the nose 29 of the pawl 26 acting against the block 31 attached to the bell 65 crank 19 will rock the bell crank and the

link 18 on their pivots 20 drawing the latch 23 out of engagement with the cut 25 and projecting the forward end 32 of the latch into the lowest one of the notches 33 in a plate 34 secured to the key bank frame 35. 70 This stops further upward movement of the latch 23 and arm 17 and downward movement of these parts because of gravitation is prevented by the rear end of the latch 23 riding on the circumference 36 of the plate 7. After the plunger 23 is disconnected from the plate 7 the latter continues to the end of its clockwise movement and then swings back to its starting point. When, during this return movement, the cut 25 is 80 brought opposite the rear end of the latch 23 the spring 24 draws the plunger into engagement with the cut, and the arm 17 and its attached parts are returned to their normal positions as shown in Fig. 1. While 85 the spring 24 is depended upon to seat the latch 23 in cut 25, additional means are provided to positively insure the return of the parts if the spring should become ineffective from any cause. To accomplish this result 90 the circumference 37 of the plate 7 has a greater radius from their common center than the circumference 36 so that as the plate 7 returns to its starting point this portion of greater radius will engage the rear 95 end of the latch 23 and draw it downward. The notches 33 and the forward end 32 of the latch 23 are so shaped that as soon as this downward movement of the latch begins the latch is cammed rearward into the cut 100 25 and the parts involved are all carried, by the completion of the operation, into the positions they occupied before the operation was begun.

The lowest notch 33 into which the latch 105 23 was projected, as just described, is the zero notch. The notch next above it is the one that the latch engages when "1" is to be registered, and so on up to the top notch which is the one engaged by the latch 23 110 when "9" is to be registered. When an amount is to be registered the position taken by the plunger 23 is determined by the keys 38. These keys are mounted radially to the shaft 6 in the frame 35 supported by the 115 cross rods 41 extending through the machine frames 11^a and the side frames 11^b. Lateral movement of the keys away from the frame 35 is prevented by guide plates 43 and 44 secured to the frames 35 and so arranged that 120 the keys are free to move endwise an extent limited in one direction by the heads of the keys and in the other direction by the shoulders 45 of the keys engaging the undersides of the plate 43. In the accompanying drawings part of the devices for latching the keys in the depressed position until they have served their purpose, the mechanism for releasing the key latches and the usual springs 125 for returning the keys to normal position 130

have been left out. These features are omitted, however, only to make the drawings more easily read and it should be understood that the machine possesses the usual 5 equipment along this line.

Adjacent to each bank of keys is a plate 46 swung from a link 47 and a pawl 48 pivotally attached at 51 and 52 respectively to the key bank frame 35. Pins 53 on this 10 plate 46 extend laterally under the keys 38. The pawl 48 has a nose 54 which engages a stud 55 in the pawl 26. When any one of the keys 38 is pressed in the cam surface 56 on its lower edge will act against the opposed pin 53 and force the plate 46 down, thereby swinging the arm 47 and the pawl 48 about their pivots and causing the nose 54 of the latter, acting against the stud 55, to draw the pawl 26 back so that its nose 29 15 will be carried out of the path of the block 31 attached to the bell crank 19. The key is then retained in the depressed position partially by pin 53 engaging the notch 566 in the lower edge of the key 38 but mainly by 20 the key latching devices mentioned above, but which are not shown in the drawings. As shown in Fig. 3 the depth of the notches 566 is such that when a key is retained in the fully depressed position the plate 46 is 25 locked down and the nose 29 of the pawl 26 is held back out of the path of the block 31 secured to the bell crank 19. This permits the arm 17 to be carried up by the plate 7 until the block 31 strikes the inwardly projecting end of the depressed key when the 30 latch 23 is disengaged from the cut 25 in the plate 7 and projected into the notch 33 corresponding to the key used. On the return movement of the plate 7, the plunger 35 23 and the plate 7 are engaged and the parts returned to normal position as described above in connection with the operation of the machine when no key in the bank was depressed. As soon as the plate 7 and the 40 arm 17 reach their normal positions the plate 46 is depressed by key releasing devices, not shown but above mentioned, and the key is then restored by its spring, permitting the 45 spring 28 to restore the pawls 26 and 48 and the plate 46 to the positions shown in Fig. 1.

As indicated in the general description of the machine given above, when an actuator moves rigidly with its carrier during its vertical movement it turns the corresponding adding wheel, but when it rotates during said vertical movement it holds the adding wheel immovable. The differential mechanism described in the immediately preceding paragraphs determines the portion, if any, of its actuating stroke that the actuator is to be effective to rotate its totalizer wheel. It will be recalled that if the machine is operated with no key in the bank depressed, the latch plunger 23 is immediately disconnected from the driving plate 7

and projected forward into the zero notch of the locking plate 34. When the mechanism is all at the starting point for an operation, the devices controlling the rotative movement of the actuators are in position to prevent rotation of the actuators so that the actuator is normally effective to drive its totalizer wheel, but when the plunger 23 is projected into the zero notch the controlling devices are shifted and the actuator immediately begins to rotate on its carrier. This rotation continues, unless interrupted momentarily as hereinafter described by a transfer from the wheel of lower denomination, during the entire reciprocation of the actuator. When the machine is operated with a key depressed the plunger 23 is not projected forward until it has been carried up to a position opposite the notch 33 corresponding to the key used. During this 80 part of the upward movement the devices controlling the rotation of the actuator remain in their normal positions and the actuator turns its adding wheel, but as soon as the plunger 23 is disconnected from the 85 driving plate 7 and projected into a notch 33 representing the key used, the controlling devices are immediately shifted to cause the actuator to rotate on its carrier during the rest of the reciprocation, except as it may be 90 interrupted by a transfer. At the end of the return to normal stroke of the actuator, regardless of whether the operation was a zero operation or an operation to register an amount, the invariably moved actuator 100 carrier restores the controlling devices to their original positions.

The controlling devices mentioned comprise a plate 57 slidably mounted on the stub shafts 58 fastened in adjacent machine frame 11^a, an arm 59 secured to a short rock shaft 60 and pivoted at its lower end to the plate 57, and an element 61 (Figs. 1 and 3) also secured to the rock shaft 60. This element 61 normally rests in the position shown in Fig. 1 with the front edge of its lower arm 62 in engagement with one of the radial slots in the edge of a disk 63 (Figs. 1 and 5) rigidly secured to the actuator 14. The arm 62 of the element 61 is 110 long enough to remain in engagement with the slots of the disk 63 during the entire actuating stroke of the actuator. Fulcrumed at 70 on the upper arm of the element 61 is a member 64 swinging from the rod 67 with 115 two teeth 65 and 66 to engage the threads of the actuator 14. The tooth 65 engages the helical portion only of the threads, while the tooth 66 engages the threads higher up and if it is in engagement when the longitudinal portion of the threads is carried into contact with it, rotation of the actuator is prevented. When the latch 23 is projected into one of the notches 33 of the locking plate 34 a stud indicated by the dotted out- 120 125 130

line 21^a and which is simply an extension of the pivot 21, strikes the bevel 67 of the corresponding notch in plate 57 and the plate is cammed upward and latched in the raised 5 position by gravity pawl 73 provided with a laterally extending lug 74 engaging a notch 75 in the upper edge of the plate. This movement of the plate 57 throws the lower end of the arm 59 toward the rear of the 10 machine and rocks the shaft 60 thereby withdrawing the arm 62 of the element 61 from engagement with the disk 63. This swings the center 70 in toward the actuator and the member 64 is swung on the pivot 67 15 from which it is suspended, so that the tooth 65 is drawn into engagement with the helical portion of the threads of the actuator, thereby causing the actuator to turn on the rod 15 as it is moved along the rod and past 20 the tooth 65. It will be seen that as long as the arm 62 is in engagement with a notch in the periphery of the disk 63 the actuator will travel rigidly with its carrier and as the threads of the actuator are at all times in 25 mesh with the teeth of the gear 68, which is rigid with the totalizer wheel 72, the totalizer wheel will be rotated, and that when the arm 62 is withdrawn and the tooth 65 swung into engagement with the threads of 30 the actuator the wheel will be held in the position that it is occupying at that time.

As previously indicated, the transfer from a wheel of lower to a wheel of higher denomination is made by rendering the actuator for the higher wheel effective to rotate its wheel one division. Each of the totalizer 35 wheels 72 is part of an element comprising the totalizer wheel, the gear 68 and a sleeve 69, all three being rigid together and rotating about a rod 71 extending through the 40 machine frames with spacing sleeves 81 (Fig. 2) holding the elements in their proper longitudinal positions on the shaft. The tooth 82 of the gear 68 is longer than the 45 other teeth of the gear and is so placed with reference to the totalizer wheel 72 that as the latter turns to carry the "9" past the reading line this long tooth will engage the lower arm 83 of a two-armed element 84 attached to one end of a short rock shaft 85 50 extending through the machine frame 11^a between the banks involved in the transfer operation and rock the shaft. Attached to the other end of the rock shaft 85 is another two-armed element 86. The lower arm of this element 86 carries a pin 87 which holds one end of a spring 88, the other end of the spring being attached to a pin 91 in the machine frame 11^a. When these parts 55 are in their normal position the line between the two pins, and, consequently, the line of the tension of the spring passes slightly below the center of the shaft 85. When the long tooth 82 of the gear 68 engages the arm 83 and rocks the shaft 85 and 60 the element 86 the line of spring tension is raised above the center of the shaft 85 and the spring then rocks the shaft still farther in a counter-clockwise direction. A link 92 connects the upwardly extending arm of 65 the element 86 and the member 64 and when the element 86 is rocked anti-clockwise through the action of the gear tooth 82 and the spring 88 this link 92 rocks the member 64 on its pivot 70 and throws the tooth 66 70 into engagement with the threads of the actuator 14 and at the same time withdraws the tooth 65, should it be in engagement with the actuator thread. If, when this movement occurs, the element 61 is positioned so that its arm 62 is still in engagement with the disk 63 of the actuator, thereby preventing rotation of the actuator and causing it to add an amount represented by a key depressed in that bank, the center 70 is 75 held away from the actuator 14 and the movement of the member 64 is stopped by the pin 79 so that the tooth 66 cannot engage the threads of the actuator. Then, when the element 61 is swung out of engagement with the disk 63 by movement of the plate 57, the center 70 is thrown in toward the actuator, thereby carrying the tooth 66 the rest of the way to bring it into engagement with the actuator threads. As 80 long as the tooth 66 is in engagement with the helical portion of the actuator thread, the actuator rotates just the same as when the tooth 65 is in engagement, but as soon as the tooth 66 comes in contact with the longitudinal portion 93 of the threads the rotation of the actuator is prevented long enough to cause it to rotate its wheel 72 one division. Just at the end of the downward 85 or actuating stroke a disk 94 carried by the actuator strikes the upper arm 95 of the element 84 and throws the tension of the spring 88 below the center of the shaft 85 so that the spring rocks the shaft 85 and the parts carried by it back to normal position. 90 This movement, through the link 92, carries the tooth 66 out of engagement with the actuator and throws the tooth 65 into engagement and the latter tooth remains in engagement until the actuator reaches its normal 95 position. Just at the end of the upward or return to normal stroke of the actuator, an extension 78 of the carrier 10 engages an arm 77 attached to the same rock shaft as the gravity pawl 73 and raises this 100 pawl out of engagement with the notch 75 in the plate 57. At this time the differential mechanism has practically completed its return movement to the normal position and the depressed key 38 is released, thereby 105 causing the nose 29 of the pawl 26 to be thrown forward above the block 31 of the latch mechanism. Releasing the key and disengaging the pawl 73 permits a spring 80 stretched between the element 61 and the 110

machine frame 11^a to restore the rock shaft 60 and the parts carried by it. This restoring movement swings the element 64 rearward to disengage the tooth 65 from the 5 threads of the actuator and also, through the arm 59, lowers the plate 57 to its original position.

The spiral arrangement mentioned above of the driving cams 2 is for the purpose of 10 operating the actuators successively, beginning with the actuator of lowest value, thereby giving time for transfers involving any number of the actuators.

While it is thought that the above detailed 15 description is clear, the following brief summary of the operation of the machine may contribute to a thorough understanding of the improvements. In the first place it should be remembered that the actuators 20 are always in engagement with their corresponding totalizer elements and that the actuators are connected to the driving mechanism by carriers which are given an invariable movement on every operation of the 25 driving mechanism. The actuators are, therefore, given a corresponding invariable movement first down and then up. In the embodiment shown all the movements imparted by them to their totalizer elements 30 are imparted during the downward movement of the actuators. In addition to this invariable movement, which is rectilinear, the actuators are capable of rotation during said rectilinear movement. When rotation 35 is prevented the actuators and their carriers move rigidly together and affect the totalizer elements the same as a rack. If the actuators are caused to rotate during the rectilinear movement the totalizer elements 40 are not rotated but are held in position by the actuators turning idly across the face of and between the teeth of the totalizer gears. When the register is at the fully operated position, that is, with all of the mechanism 45 ready for the next operation, the driving mechanism and the differential mechanism of the different banks are connected by the plungers 23 carried by the differential mechanism being in engagement with the plate 7 50 of the driving mechanism and the devices controlling the rotation of the actuator are in engagement with the notched disk rigidly connected to the actuators. If the machine was operated with the parts in these positions 55 the actuator would travel vertically first down and then up without rotation and act as a rack to rotate the totalizer wheel. However, the pawl 26 is normally held by its spring in such a position that if an attempt 60 is made to operate the register with no key depressed, this pawl will immediately disconnect the differential mechanism from the driving mechanism by drawing the plunger 23 out of engagement with 65 the plate 7. As the plunger is drawn out

of engagement a stud moving with it engages the bevel upper side of the lowest or zero notch in the plate 57 sliding the plate upward and toward the rear of the machine, in which position it is latched by a gravity 70 pawl. This plate is pivotally connected at its upper end with an arm 59 attached to the rock shaft 60 which carries the element 61, and as the plate 57 moves up and rearward this shaft is rocked to carry the arm 75 62 of the element 61 out of engagement with the notched disk attached to the actuator. This movement of the element 61 throws its upper end toward the actuator and carries the lower tooth 65 of a member 64, swung 80 from the pivot 67, into engagement with the threads of the actuator. The movement just described occurs at the very beginning of the operation of the machine before the actuator has had time to rotate the totalizer 85 wheel an appreciable extent. If no transfer is turned in from the next lower bank the tooth 65 remains in engagement and the actuator rotates idly until the end of the reciprocation, when the shaft 60 is rocked 90 in the other direction or back to its original position, bringing the arm 62 of the element 61 into engagement with the actuator and throwing the tooth 65 out of engagement 95 with the threads of the actuator, thereby restoring the devices ready for the next operation. If, during this zero operation, a transfer is turned in from the next lower wheel the operation is the same except that when the long tooth 82 of the totalizer gear 100 reaches the proper point in the rotation it trips the transfer devices and the link 92 to which the member 64 is pivoted is thrown toward the front of the machine. The pivot 70 of the member 64 then acts as a fulcrum 105 about which the member 64 operates and the tooth 65 is withdrawn from engagement with the actuator threads and the tooth 66 thrown into engagement. In other words the control of the rotation of the actuator 110 is instantaneously transferred from the tooth 65 to the tooth 66 and the tooth 66 will then be effective when the longitudinal section 93 of the actuator threads strike it to stop rotation of the actuator and cause the actuator 115 to rotate its totalized element. Just at the end of the downward movement of the actuator the disk 94 restores the tripped transfer devices to their original position and the tooth 65 is then in engagement with 120 the actuator threads while the actuator is carried back up to its starting point. Just as it reaches its original position an extension on the actuator carrier releases the gravity pawl which latches the plate 57 in 125 the raised position and the actuator controlling devices are all restored to normal with the element which prevents rotation of the actuator in engagement. If a key in a bank is depressed the disconnecting pawl 26 is 130

drawn back out of way and the differential mechanism is not disconnected from the driving mechanism until the tripping devices for the latch 23 strike the inwardly extending end of the depressed key. During the travel from the starting point to the point where the key disconnects the differential and the driving mechanism the actuator is held against rotation but moves vertically in the usual way and it therefore turns its totalizer element a distance corresponding to the value of the key depressed. As soon as the differential mechanism and the driving mechanism are disconnected the operation of the actuator either idly to hold the totalizer wheel in position or when interrupted by a transfer from the lower bank, is the same as described in connection with the zero operation. In other words the extent of rotation that the actuator can give its totalizer element is determined by the distance the differential mechanism is carried up from the starting point before it is disconnected from the driving mechanism. If it is disconnected at the start of the operation, nothing is registered. If it travels up, for example, to the five key, the actuator will be effective to rotate its totalizer wheel five divisions before it is rendered ineffective by the shifting of the controlling devices.

While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the claims which follow.

What is claimed is:—

1. In a machine of the class described, the combination of a member to be driven in one direction only, a driving member constantly in engagement with the driven member and having an invariable extent of movement, and manipulative means for predetermined the distance the driving member is to drive the driven member.
2. In a machine of the class described, the combination of a member to be driven in one direction only, a driving member constantly in engagement with said driven member and having an invariable extent of movement, means normally preventing said driving member from moving the driven member, and manipulative devices for disabling said preventing means and predetermined the distance the driving member is to drive the driven member.
3. In a machine of the class described, the combination of a member to be driven in one direction only, a driving member constantly in engagement with the driven member and having an invariable extent of move-

ment, manipulative devices, and means controlled by said manipulative devices whereby the invariably moved driving member will differentially move said driven member.

4. In a machine of the class described, the combination with an operating mechanism, of a driving element given invariable excursions by operations of the operating mechanism, a driven element constantly in engagement with and driven in one direction only by said driving element, and manipulative means whereby the driving element may be rendered effective to drive the driven element predetermined distances during one direction of the invariable excursion and ineffective during the remainder of the excursion.

5. In a machine of the class described, the combination of a driving member and a driven member, said driven member being at all times in engagement with the driving member and designed to be driven in one direction only, means whereby the driving member is reciprocated an invariable distance, and manipulatively controlled devices for predetermined the distance the driving member is to drive the driven member and rendering the driving member effective to hold the driven member stationary during the remainder of the reciprocation of the driving member.

6. In a machine of the class described, the combination with a driven element comprising a gear, a rotatable driving element having a helical thread always in engagement with said gear, a positively operated carrier for giving said actuator an invariable excursion, and manipulative devices under the control of which said driving element will move rigidly with its carrier to drive the driven element and then rotate on its carrier during the remainder of its excursion to hold the driven member in position.

7. In a machine of the class described, the combination with a driven element comprising a gear having spirally disposed teeth, a rotatable driving element having a helical thread always in engagement with said gear, a positively operated carrier giving said actuator an invariable excursion, and manipulative devices under the control of which said driving element will drive the driven member to a predetermined position and then hold it in that position.

8. In a machine of the class described, the combination of a rotatable member, a member constantly in engagement with the rotatable member and having an invariable extent of movement, and manipulative devices under the control of which said invariably moved member will differentially rotate the rotatable member.

9. In a machine of the class described, the combination with an operating mech-

- anism, of a rotatable element bearing a plurality of characters only one of which is to be effective at a time, a driving member permanently in engagement with said 5 rotatable member and reciprocated an invariable distance on every operation of said operating mechanism, and manipulative devices under the control of which said driving member may be caused to rotate the 10 rotatable element to render any desired one of its characters effective.
10. In a machine of the class described, the combination with an operating mechanism, of a rotatable element, a driving member at all times in engagement with said rotatable element and reciprocated an invariable distance on all operations of the operating mechanism, and manipulative means whereby the driving element may be 15 rendered effective to rotate the rotatable element predetermined distances during one direction of the reciprocation and ineffective during the remainder of the reciprocation.
11. In a machine of the class described, the combination with an operating mechanism, of a totalizer comprising a plurality of rotatable elements, a plurality of actuators, said actuators being at all times in engagement with their corresponding totalizer 20 elements, means whereby said actuators are reciprocated an invariable distance on all operations of the operating mechanism, and manipulative means for predetermining the distance the actuators are to rotate their respective totalizer elements during the reciprocating movement of the actuators.
12. In a machine of the class described, the combination with an operating mechanism, of an accounting device comprising a 25 plurality of rotatable elements, a plurality of driving elements for said rotatable elements, said driving elements being at all times in engagement with the rotatable elements and reciprocated invariable distances 30 on all operations of the operating mechanism, and manipulatively controlled devices for predetermining the extent of rotation the driving elements are to give their accounting device elements and rendering the 35 driving elements ineffective to drive their accounting elements during the rest of the reciprocating movements of the drivers.
13. In a machine of the class described, the combination with an operating mechanism, of an accounting device comprising a 40 plurality of rotatable elements, a plurality of driving elements for said rotatable elements, said driving elements being at all times in engagement with the rotatable elements and receiving excursions of an invariable distance on all operations of the operating mechanism, and manipulative devices under the control of which said driving elements will differentially rotate the 45 aforesaid rotatable elements during the ex- 50 cursions of the driving elements and render said driving elements effective to hold the rotatable elements stationary during the rest of the excursions.
14. In a machine of the class described, 70 the combination of a rotatable totalizer element, a rotatable actuator constantly in engagement therewith and having an invariable rectilinear movement, and means for rotating the actuator during its rectilinear movement thereby preventing the actuator from rotating its totalizer element.
15. In a machine of the class described, the combination with a totalizer comprising a series of movable elements, of a series of 75 actuators, said actuators being constantly in engagement with their respective totalizer elements, devices for giving the actuators an invariable extent of movement, manipulative devices, and means controlled by the 80 manipulative devices for causing the invariably moved actuators to differentially move the totalizer elements.
16. In a machine of the class described, the combination with an operating mechanism, of a totalizer comprising a series of 85 movable elements, actuators at all times in engagement with the movable totalizer elements and being reciprocated an invariable distance on all operations of the operating mechanism, a plurality of manipulative devices, and means controlled by said manipulative devices for predetermining the distances the actuators are to move their totalizer elements during the reciprocating 90 movement and disabling the actuators during the remainder of their reciprocations.
17. In a machine of the class described, the combination with an operating mechanism, of a totalizer comprising a series of 95 movable elements, actuators, said actuators being at all times in engagement with the totalizer elements and moving an invariable extent on all operations of the operating mechanism, a series of keys, and means controlled by said keys for predetermining the 100 extents of movement to be given said movable elements by the actuators on operations of the operating mechanism.
18. In a machine of the class described, 115 the combination with an operating mechanism, of a totalizer wheel, an actuator for said totalizer wheel, said actuator being constantly in engagement with said totalizer wheel and having an invariable extent of 120 movement on all operations of the operating mechanism, manipulative devices, and means controlled by said manipulative devices for causing said invariably moved actuator to differentially rotate the totalizer wheel.
19. In a machine of the class described, 125 the combination with an operating mechanism, of a totalizer, actuators for said totalizer, said totalizer and actuators being at all times in engagement, means for giving 130

the actuators invariable excursions on all operations of the operating mechanism, and manipulative devices for predetermining amounts to be entered in the totalizer by the 5 actuators.

20. In a machine of the class described, the combination with an operating mechanism, of a totalizer, invariably moved actuators for said totalizer, said actuators and 10 totalizer being at all times in engagement, and manipulative devices for predetermining amounts to be entered in the totalizer by the actuators and rendering the actuators ineffective to operate the totalizers after the 15 proper entry has been made.

21. In a machine of the class described, the combination with an operating mechanism, of a totalizer unit designed to be turned in one direction only, an actuator, 20 said actuator being at all times in engagement with the totalizer unit and being given an invariable extent of movement on all operations of the operating mechanism, manipulative devices, and means controlled 25 by said manipulative devices whereby said actuators may be rendered effective to turn the totalizer unit desired distances and then rendered effective during the remainder of the invariable movement to retain the totalizer unit in the position to which it was 30 turned.

22. In a machine of the class described, the combination of a totalizer having a plurality of rotatable elements, actuators, said 35 actuators being at all times in engagement with the rotatable elements, devices for carrying said actuators an invariable distance, and means normally causing the actuators to rotate on their carriers to prevent them 40 from rotating their totalizer elements.

23. In a machine of the class described, the combination with a totalizer unit comprising a gear having spirally disposed teeth, of a rotatable actuator having a helical 45 thread always in engagement with said gear teeth, a carrier for said actuator, said carrier giving the actuator an invariable rectilinear movement, and devices for causing the actuator to rotate on its carrier during 50 said rectilinear movement, thereby holding the totalizer unit stationary.

24. In a machine of the class described, the combination with a totalizer unit comprising a gear, of a rotatable actuator having 55 a helical thread always in engagement with said gear teeth, a carrier for said actuator, said carrier giving the actuator an invariable rectilinear movement, and manipulative devices under control of which rotation of the actuator on its carrier may be 60 prevented.

25. In a machine of the class described, the combination with a rotatable totalizer unit comprising a gear having spirally disposed teeth, of a rotatable actuator having 65

a helical thread always in engagement with said gear teeth, a carrier for said actuator, said carrier giving the actuator a rectilinear movement of invariable extent, devices normally causing the actuator to rotate on its carrier during said rectilinear movement thereby holding the totalizer unit stationary, and manipulatively controlled means for disabling said devices and causing the actuator to move rigidly with its carrier thereby rotating the totalizer element. 75

26. In a machine of the class described, the combination with a totalizer comprising a plurality of rotatable elements, of a plurality of actuators at all times in engagement with and normally effective to rotate said totalizer elements, devices for giving said actuators invariable excursions, a plurality of keys, differential mechanism controlled by said keys, a detent operated by 80 said differential mechanism, and devices operated by said detent for rendering the actuators ineffective to rotate the totalizer elements and effective to hold said elements 85 stationary. 93

27. In a machine of the class described, the combination with a plurality of adding wheels, of a series of invariably moved actuators at all times in engagement with the corresponding adding wheels, means operated 95 by lower denomination adding wheels whereby the next higher denomination actuators are enabled to perform carrying operations, and elements carried by the actuators for restoring said means to normal. 100

28. In a machine of the class described, the combination with a plurality of adding wheels, of a series of invariably moved actuators at all times in engagement with their corresponding adding wheels, and means 105 operated by lower denomination adding wheels whereby the next higher denomination actuators are enabled to perform carrying operations.

29. In a machine of the class described, the combination with a totalizer comprising a plurality of rotatable elements, of a plurality of actuators at all times in engagement with and normally effective to rotate said totalizer elements, devices for giving 110 said actuators invariable excursions, a plurality of keys, differential mechanism controlled by said keys, a detent operated by said differential mechanism, and devices operated by said detent for rendering the actuators ineffective to rotate the totalizer elements. 115

30. In a machine of the class described, the combination with a driving mechanism, of a plurality of rotatable totalizer elements, 120 a plurality of actuators at all times in engagement with and normally effective to rotate said totalizer elements, devices for giving said actuators invariable excursions on all operations of the driving mechanism, a 125 130

- plurality of keys, devices differentially positioned under control of said keys, a detent operated by said differentially positioned devices, and mechanism operated by said 65
 5 detent for rendering the actuators ineffective to rotate the totalizer elements and effective to hold the said elements stationary.
31. In a machine of the class described, the combination with a main operating 10 mechanism, of a rotatable totalizer element, a rotatable actuator always in engagement with said element and having an invariable rectilinear movement, a plurality of manipulative devices, devices differentially positioned 15 under control of said manipulative devices by operations of the operating mechanism, a normally ineffective detent rendered effective by positioning the differential devices, and devices controlled by said detent comprising an element preventing rotation of the actuator when the detent is in ineffective position and a second element causing rotation of the actuator when the detent is in effective position.
- 20 32. In a machine of the class described, the combination with a rotatable totalizer element comprising a gear having spirally disposed teeth, of an actuator for said element having a helical thread always in engagement with said gear, a slotted disk carried by said actuator, a plurality of manipulative devices, differential mechanism operating under control of said manipulative devices, a detent operated by the differential 25 mechanism, and devices operated by said detent comprising an element engaging the aforesaid slotted disk when said detent is in normal position and a second element engaging the helical thread of the actuator 30 when the detent is in operated position.
33. In a machine of the class described, the combination with a driving mechanism, of a plurality of totalizer elements, an actuator constantly in engagement with each of 35 said elements, means whereby all actuators are given an invariable movement by operations of the driving mechanism, manipulatively controlled means for rendering the actuators ineffective to drive their totalizer 40 elements during differential portions of said invariable movement, and means controlled by the totalizer elements for rendering the actuators of the next higher elements effective to rotate their respective totalizer 45 elements one division.
34. In a machine of the class described, the combination with a driving mechanism, of a plurality of totalizer elements, an independent actuator for each element, said 50 actuators being at all times in engagement with their respective elements, means whereby all actuators are given an invariable movement by operations of the driving mechanism, and means controlled by the 55
- totalizer elements for rendering the actuators of the next higher elements effective to rotate their respective elements one division.
35. In a machine of the class described, the combination with a totalizer element, of an actuating device permanently connected thereto constructed to actuate the totalizer element in adding and carrying operations and to hold said element against movement in either direction between such operations. 60
36. In a machine of the class described, the combination with a digit carrier to be driven in one direction only, of an invariably moved actuator constantly in engagement with said digit carrier, means for rendering said actuator effective and ineffective to drive the digit carrier during differential portions of its invariable movement, and manipulative devices for controlling said means.
37. In a machine of the class described, the combination with a digit carrier, of an invariably moved element constantly in engagement with the digit carrier, means for rendering the invariably moved element effective to drive the digit carrier during differential portions of the invariable movement and ineffective during the rest of said movement, and manipulative devices for controlling said means.
38. In a machine of the class described, the combination with a digit carrier, of an actuator constantly in engagement therewith, said actuator having a reciprocatory movement and being capable of rotary movement during its reciprocatory movement, means for preventing rotary movement of the actuator during differential portions of its reciprocatory movement whereby to differentially drive the digit carrier, and manipulative devices for controlling said means.
39. In a machine of the class described, the combination with an operating mechanism, of a rotatable member designed to be rotated in one direction only, a driving member constantly in engagement with said rotatable member and making an excursion of invariable extent on all operations of the operating mechanism, and manipulatively controlled devices for predetermining the degree of rotation to be given the rotatable member by the driving member and disabling the driving member during the remainder of its excursion.
40. In a machine of the class described, the combination with a series of totalizer elements, of a series of actuators appropriate thereto and constantly in engagement therewith, said actuators having a reciprocatory movement and being capable of rotary movement during their reciprocatory movements, means for preventing rotary

movement of the actuators during differential portions of their reciprocatory movements whereby to differentially drive the totalizer elements, manipulative devices for controlling said means, and means actuated by the totalizer elements for preventing rotation of higher order actuators whereby to effect carrying operations.

In testimony whereof I affix my signature in the presence of two witnesses.

THOMAS MIDGLEY, JR.
